(57) **CLAIM**

I claim the ornamental design for a bag, as shown and described.

DESCRIPTION

FIG. 1 is a front right perspective view of a bag showing my new design in an open configuration with the backpack straps shown snapped together;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front left perspective view thereof;

FIG. 9 is a front right perspective view thereof, with the backpack straps shown un-snapped;

FIG. 10 is a front left perspective view thereof;

FIG. 11 is a front and top perspective view of the bag folded and shown in a handbag configuration;

FIG. 12 is a rear and bottom perspective view thereof;

FIG. 13 is a front and top perspective view of the bag folded into a backpack configuration with the rear straps shown snapped together;

FIG. 14 is a rear and bottom perspective view thereof;

FIG. 15 is a front and top perspective view thereof with the backpack straps shown un-snapped; and,

FIG. 16. is a rear and bottom perspective view thereof.

1 Claim, 16 Drawing Sheets
